UNITED STATES PATENT OFFICE

EARLE E. SMITH, OF WEST SPRINGFIELD, MASSACHUSETTS

COMBINED STREET AND TRAFFIC SIGN

Application filed April 28, 1932. Serial No. 607,939.

My invention relates to improvements in combined street and traffic signs.

An object of my invention is to provide, incorporated in a single sign post, means for legibly displaying all required, or desirable, information regarding locality, direction, and traffic regulations.

A further object of my invention is to provide a sign post which will display such information adequately at all times, both day and night. At the present time, a majority of the street signs now in use are painted metal signs, and many of these are so situated as to be unreadable after dark. Many of the traffic, or directional signs, in use are also painted signs, with no provision made for illumination at night. This lack of visibility of such directional and warning signs at night is the cause of a great many accidents. It is the purpose of my invention to provide, in such a sign post means for illuminating the information presented thereon, in such a manner as to make it clearly legible from any reasonable distance, at all times.

Broadly, my invention comprises a post member having signs and directions painted on its sides, a sign box secured to the top of said post, signs on the sides, ends, and bottom of the sign box, a glass top on the sign box, and means within the box for illuminating the signs on the box and the sign on the sides of the post, at night.

A preferred form of my sign post is illustrated in the accompanying drawings, in which Fig. 1 is a diagrammatic view illustrating the location of my sign posts on highway and cross streets.

Fig. 2 is a side elevational view of a sign post having a round post member designed to be set in the ground.

Fig. 3 is an end view of the post, shown in Fig. 2, looking from the left.

Fig. 4 is a view of the opposite end of the post, shown in Fig. 2, looking from the right.

Fig. 5 is an elevational view of a preferred form of sign post having a post member that is rectangular in cross section, and showing the street side of the post.

Fig. 6 is an end view of the sign post, shown in Fig. 5.

Fig. 7 is an elevational view of the sidewalk side of the post member, shown in Fig. 5.

Fig. 8 is an underside plan view taken on the line 8-8 of Fig. 5, showing the compass. 55

Fig. 9 is a longitudinal sectional view through the sign box.

Fig. 10 is a cross sectional view on the line 10-10 of Fig. 9, and

Fig. 11 is an enlarged detail sectional view, 60 illustrating the construction of the top frame of the sign box which permits removal of the top, side, and end panels of the sign box.

Referring now to the drawings in detail, in which like numerals refer to like parts 65 throughout:

As indicated in Fig. 1, the sign posts, or traffic signs, 1, are placed near the intersection of the highway 2 and cross streets, 3, 4, 5, and 6. The posts 1 are so placed that the long axis of the sign box is parallel with the street whose name the sign bears. 70

Figs. 2, 3, and 4 illustrate a sign post, which may be used at the intersection of a highway and a one-way street. The round post 7 has secured thereto the sign box 8, in which are removably secured the metal perforated signs, (see Figs. 10 and 11), and the translucent end panels 10 and 11. The top, or cover 12, of the sign box 8 is made of some suitable transparent material, such as glass, or celluloid, for the purpose of admitting light during the day time to the interior of the sign box 8. The metal signs 9 are perforated to form letters 13, indicating the name of the street and the direction in which traffic is permitted to proceed, or any other desired information. They may be so perforated, as to form openings in the shape of an arrow, or similar devices. At each end 80 of the sign 9 an opening 15 is formed, for the purpose of indicating to the driver of a motor vehicle the nature or meaning of the sign on the end panel, next adjacent to said opening. 85

The translucent end panels 10 and 11, (see Figs. 3 and 4) are colored and lettered to indicate the desired information. For the purposes of illustration, I have shown the words "stop" and "go," at 16 and 17, respectively. Many serious accidents are caused, 90 95 100

at the present time, by the fact that traffic directions are indicated by color only, and a large number of drivers of motor vehicles are partially, or wholly, color blind. For this reason, the translucent end panels 10 and 11 are provided with distinctive markings which are clearly visible at a greater distance than that at which the letters become legible. For the purposes of illustration, I have shown a band, or bar 18, of white on a red background for the "stop" signal and a diamond-shaped figure of white, 19, against a green background, for the "go" signal. The sides of the post 7 are painted with letters 20 and 21 and colors of the backgrounds 22 and 23, corresponding with the end panels 10 and 11 of the sign box 8.

Figs. 5, 6, and 7 illustrate a preferred form of sign post, in which the post is rectangular in cross section, thus providing four flat sides on which are painted any desired information. The hollow post 24 is formed with the tapered sides 25 and 26, the base member 27 and cap member 28. The sign box 8 is secured to the reinforcing, or supporting plate 29, which is in turn secured to the cap member 28. The cap member 28 is formed with perforations 30 and a horn, or bell 31, indicated by dotted lines in the form of a circle and on the drawings by the words "electric bell," is secured within the cap member 28 and connected to an electric warning circuit, (not shown), to warn drivers at times of fog, or of the fact that they are approaching a point of street intersection.

The sign box 8 is formed with the bottom plate, or member 32, top frame 33, and corner posts 34. Electric lamps 35, as shown in Fig. 9, are removably secured in the sockets 36, within the sign box 8 and connected to the regular street lighting circuit, (not shown). The bottom plate 32 is formed with the openings 37 and 38, and is covered on the inside, or upper surface, with the thin sheet 39 of highly reflective translucent material, such as white mica, white glass, or some similar suitable substance. The reinforcing plate 29 is formed with openings 37' registering with the openings 37. The sheet 39 is painted, or otherwise marked, with the points of the compass over the opening 38, as indicated at 40, in Fig. 8. Light entering through the transparent top member 12 in the daytime, or from the lamps 35 at night, is projected downward through the openings 37 and 37' onto the sides of the tapered post 24, thus illuminating the signs, which are painted on the post 24, as shown in Fig. 5. Similarly, the dial 40, indicating the points of the compass, is illuminated from above. The perforated metal sign plates 9 are covered on the inside with translucent and light reflection sheets 41, similar to the sheet 39, and are painted, or otherwise colored, at 42 and 43, for registering with the openings 15,

to correspond with the color of the background of the adjacent end panels 10 and 11, respectively. In daylight, light entering through the top 12 illuminates the post 24, dial 40, perforated metal sign plates 9, and translucent end panels 10 and 11. At night, the lamps 35 perform the same function.

The top member 12, signs 9, and end panels 10 and 11 are removable and interchangeable. The top, or corner frame member, 33, of the sign box 8, is left open at one end, as indicated at 44, in Fig. 9. The top 12 may be removed by sliding it out of this open end 44. After the top 12 is removed, the signs 9 and ends 10 and 11 may be removed by pulling upward through the open top of the box 8. The corner posts 34 of the box 8 are inclined outwardly from the bottom to the top, thus supporting the signs 9 at an angle to the vertical. This angle presents the signs 9 in a legible position to a person situated close to the sign post 24, as well as to those at a distance. The top member 12 is formed with the slightly pitched upper surface 45, for the purpose of shedding rain, and the top frame 33 is channel-shaped in cross section, as indicated in Fig. 11, and formed with a plurality of openings 46, for the purpose of draining any water which may collect in the frame 33 from the pitched top surface 45.

What I claim is:

1. A street and traffic sign post comprising in combination, a hollow post member having signs on the sides of said post member, an audible signal device located within said post member, a sign box secured to said post member, a transparent top member removably secured in said sign box, corner posts in said sign box formed with grooves open at the top of said corner posts and normally covered by said top member, side and end sign panels slidably secured in the grooves in said corner posts whereby said side and end panels may be removed from said sign box after the top member has been removed, and means for illuminating the interior of said sign box and the sides of said post.

2. A street and traffic sign device comprising, in combination, a post member rectangular in cross section, a sign painted on each of the sides of said post, a sign box secured to said post member, a transparent top member removably secured to said sign box, perforated sign panels removably secured to said sign box, translucent end panels having painted thereon traffic directions, the end panels being removably secured in said sign box, and means for illuminating the interior of said sign box comprising a plurality of electric lamps secured within said sign box, and connected in a street lighting circuit.

3. A street and traffic sign post, comprising in combination, a post member having signs marked on its sides, a sign box secured to said post, a transparent top member re-

movably secured to said sign box, side and end sign panels removably secured in said sign box, a bottim plate member secured to said sign box and formed with a plurality of openings, a compass dial secured over one of the openings formed in said bottom plate, a translucent and reflective lining material secured within said sign box, and a plurality of electric lamps secured within said sign box, for the purpose of projecting light through said side and end sign panels and through the openings in said bottom plate member onto the sides of said post for illuminating the post member.

4. A street and traffic sign post comprising, in combination, a post member, a sign box secured on said post member, street signs removably secured in the sides of said sign box, translucent end panels provided with contrasting designs in co-operation with the words "stop" and "go" removably secured in the ends of said sign box, and means for illuminating the interior of said sign box by daylight and by electric lamps.
